Primary Examiner — Christy Nemeth

(57) **CLAIM**

The ornamental design for a magnetic power bank, as shown and described.

DESCRIPTION

FIG. 1 is a top, left and back side perspective view of a magnetic power bank with its stand in open state, showing the new design;

FIG. 2 is a bottom, left and front side perspective view of the magnetic power bank with its stand closed, showing the new design;

FIG. 3 is a top, right and back side perspective view thereof;

FIG. 4 is front elevational view thereof;

FIG. 5 is a back elevational view thereof;

FIG. 6 is a right side elevational view thereof;

FIG. 7 is a left side elevational view thereof;

FIG. 8 is a top plan view thereof; and,

FIG. 9 is a bottom plan view thereof.

The broken lines in the drawings are for the purpose of illustrating portions of the article that form no part of the claimed design.

1 Claim, 9 Drawing Sheets
